UNITED STATES PATENT OFFICE.

FRANCIS X. MALOCSSAY, OF NEW YORK, N. Y., ASSIGNOR TO INTERNATIONAL BANDING MACHINE COMPANY, OF NEW YORK, N. Y., A CORPORATION OF NEW YORK.

CIGAR-BANDING MACHINE.

Application filed December 9, 1920. Serial No. 429,536.

This invention relates to a machine for placing bands on cigars, and the object of this invention is to provide a machine of this character which will rapidly and accurately apply the bands to the cigars.

A further object of this invention is to provide a machine of this character which will be comparatively simple in construction and small in size, thereby occupying but little space and being free from the complex mechanisms usually found in machines of this kind.

With these objects, and other objects which may hereinafter appear, in view, I have devised the particular arrangement of parts hereinafter set forth, and more particularly set forth in the claims appended hereto.

Reference is to be had to the accompanying drawings, forming a part hereof, in which

Figure 1 is a front elevation of my improved machine;

Figure 2 is a front elevation of my improved machine, showing the same in the act of beginning the folding of a band about a cigar;

Figure 3 is a plan view of the machine;

Figure 4 is an elevation of one side of the machine;

Figure 5 is an elevation of the opposite side of the machine;

Figure 6 is a sectional view on the line 6-6 of Figure 3 looking in the direction of the arrows;

Figure 7 is a rear elevation of the machine;

Figures 8, 9 and 10 are views of the band-folding mechanism, showing the manner in which a band is placed about a cigar;

Figure 11 is a front elevation of the mechanism for folding the bands about a cigar.

Throughout the various views of the drawings similar reference characters designate similar parts.

In the preferred embodiment of my invention, as disclosed in the accompanying drawings 1 indicates the base plate of the ma-

chine, on which is mounted the frame, said frame having a front plate 2 and a rear plate 3. The frame is likewise provided with bearings 4 and 5 in which is journaled the drive shaft 6.

Mounted on the drive shaft 6 is a wheel 7, which may be used to operate the machine by hand if desired, and which is provided with a groove 8 to receive a driving belt when the machine is power driven.

Fixed on the shaft 6 is a spiral gear 9 which meshes with and drives a gear 10, which gear 10 is driven at right angles to the gear 9. The gear 10 is fixed on a shaft 11, mounted in bearings 13 on the frame of the machine. Fixed on the shaft 11 is a pair of interrupted gears 14 and 15. The gear 14 acts to drive the mechanism which folds the bands about the cigars, and the gear 15 acts to drive the cigar-holding and band magazine reciprocating mechanism in a manner to be hereinafter described.

At 16 is a shaft which is journaled in bearings 17 and 18 in the frame. Secured at the end of the shaft 16 is an interrupted gear 17' which meshes with the interrupted gear 15 and is driven thereby. Fixed on the end of the shaft 16 is a crank arm 18' which is pivotally connected to the lower end of a vertically extending link 19. The link 19 extends upwardly and is pivotally connected at its upper end to an arm 20 which has its front end downwardly bent at 21. The lower end of the arm 21 is provided with a foot 22 which contacts with the cigar 23 and moves it downward and holds it upon its support while the banding operation takes place. To permit the band to be applied to the cigar 23 without interference by the foot 22 which rests on the cigar, the foot 22 is cut away or recessed as at 24.

The arm 20 is fixed upon a vertically reciprocable shaft 25 which slides in bearings 26 and 27 projecting from the rear of the frame of the machine.

Fixed on the shaft 25 and therefore movable therewith, is a bent arm 28 which projects outwardly from the shaft 25 and extends towards the front of the machine and

terminates in a bracket 29 which supports the band magazine.

The arm 28 is provided with a yoke 30 which embraces and slides on an upwardly extending square rod 31 fixed in a projecting ear 32 on the frame and secured therein by means of the nut 33 on the threaded end 34 of the rod 31. The rod 31 thus acts as a guide for the arm 28 and assures proper vertical movement thereof.

The bracket 29, which is a continuation of the arm 28, and which supports the band magazine, is in the nature of a yoke-shaped member having a pair of upwardly extending side arms 35 terminating in guides 36 (see Fig. 2).

V-shaped end members are indicated at 37 and are provided with projecting pins 38 which extend in the guides 36 and may be fixed at any desired position therein whereby the end members 37 of the magazine may be fixed at various distances apart from one another to accommodate various lengths of cigar bands in the magazine.

To hold the end members 37 of the magazine in proper alignment guide-pins 39 are provided on the bracket 29 and these guide pins pass through the lower ends of the magazine end members 37.

A plate 40 forms a band support or carrier for the stack of bands 42 and this plate is fixed upon the upper end of a rod 41 which is vertically movable to elevate the pile of bands 42 as these bands are successively removed and applied to the cigars. The plate 40 and end means 37 thus constitute the band magazine. The rod 41 is frictionally and slidably held in guide bearings 43 and 44 on the bracket 29 and is automatically raised in said guides as fast as the bands are removed.

To elevate rod 41 and consequently the plate 40 and the stack of bands resting thereon, I provide mechanism as follows:

A plate 45 carried by rod 41 rests upon the upper face of the bearing 44 in bracket 29. Plate 45 has a perforation to loosely fit an upwardly projecting pin 46 on the bearing 44. Plate 45 has another perforation to loosely fit around rod 41.

A bracket 48 is secured to the front plate 2 of the frame. As the rod 41 moves downward with bracket 29, an edge of plate 45 strikes bracket 48, canting said plate and causing it to frictionally grip and arrest further downward movement of rod 41, and as end members 37 and bracket 29 continue to descend rod 41 is raised relative to said bracket 29 and consequently plate 40 and the stack of bands carried thereby is raised relative to said end members 37. Frictional resistance in guides 43 and 44 holds rod 41 in the position to which it has been raised relative to bracket 29.

Therefore, as foot 22 is brought down to hold a cigar, bracket 29 will descend because

both are carried by shaft 25. But as downward movement of rod 41 is arrested in the manner described and stack 42 raised relative to end members 37, it will be seen that the stack of bands 42 is moved upward step 70 by step to maintain the top of the stack at the same elevation relative to the end members 37, whether the number of bands in the stack are many or few.

Secured on the drive shaft 6 of the machine is a cam 49 which acts on a roller 50 mounted on a pin 51 projecting from a lever 52. The lever 52 is pivoted at its lower end on a pin 53 secured in an ear 54 on the frame of the machine. Adjacent to the upper end of the lever 52 is secured a moistening receptacle 55. Secured on the upper end of the lever 52 is a bracket 56 which holds a tubular finger 57. The outer end of the finger 57 is downwardly bent in proper position to pick up a band from the top of the band stack 42 in the magazine. A suitable moistening wick 58 extends through the finger 57 and has one of its ends lying in the moistening receptacle with its other end slightly projecting out of the end of the finger 57 and adapted to contact with the gummed end of a band and remove the same from the band stack. By means of the cam mechanism just referred to, it will be seen that the band picking finger 57 has a backward and forward movement, that is, it removes a band from the band stack 42 and carries the band backward for a short distance so that said band is held directly over the band folding 100 mechanism. After the application of the band to the cigar the finger is moved forward to receive another band from the stack. This operation is continually repeated while the machine is in operation.

At 59 is shown an arm extending laterally from the frame of the machine. This arm 59 is secured to a portion of the frame, as by the screws 60 and 61. Projecting from the end of the arm 59 is a rod 62 on which is pivotally mounted a support in the form of a table or plate 63.

The table 63 is cut away as at 64, thus dividing its free end into two portions 65 and 66. This table 63 acts as a support for the 115 ends of the cigar 23 while the banding operation takes place. The cigar 23 thus rests upon the ends 65 and 66 of the supporting table while the banding mechanism moves into the cut-away portion 64 of the table 63 120 and applies the band to the cigar.

A guide 67 is adjustably secured on the part 66 of the table, said guide being slotted as at 68 and an adjusting screw 69 enters said slot and fixes the guide in any desired position. On the part 65 of the table is adjustably secured an end guide 70 which is slotted as at 71 and has an adjusting screw 72 whereby the guide may be regulated to properly position various lengths of cigars. By 130

means of the positioning guides 67 and 70 it will be seen that cigars may be readily placed in proper position on the table 63 to receive the band.

5 Secured at the pivoted end of the supporting table 63 is a counter weight 73 which tends to keep the table in its horizontal position. As will be seen in Figure 2 the contact of the foot 22 on the arm 20 with the 10 cigar 23 which is resting on the table 63 causes the table to be swung downwardly. As soon as the banding operation is completed, in a manner to be hereinafter described, the weight 73 swings the table 63 15 upwardly about its pivot 62, until it reaches its horizontal position disclosed in Figure 1. The table is restricted in its upward pivotal movement by means of a stop 74 projecting outwardly from the arm 59.

20 The mechanism for folding the band about a cigar will now be described. The interrupted gear 14 on the shaft 11 meshes with and drives a gear 75 mounted on a shaft 76 which rotates in bearings 77 and 78 25 of the frame. Fixed on said shaft 76 are two cams 79 and 80 which actuate the band-folding arms. The band-folding arms are indicated at 81 and 82. Each one of these arms is provided with a central hub 83. 30 The arm 81 has its hub 83 pivotally mounted on a spindle 84 and extending downwardly from the hub is an arm 85 on the lower end of which is mounted a cam roller 86 which rides on the cam 79 and is actuated thereby.

35 The band-folding arm 82 is provided with a downwardly extending arm 87 which is similar to the arm 85, and which is provided with a cam-roller 88 which rides on the cam 80 and is actuated thereby.

40 The band-folding arms 81 and 82 are provided at their upper ends with the band-folding fingers 89 and 90 which are pivoted at 91 and 92 respectively. Each of the folding fingers 89 and 90 is provided with a stop 93 which abuts against the arms 81 or 82. At 94 is indicated a cigar supporting platen 94 which is in the nature of a plate and which is fixed on top of a downwardly 45 movable resiliently mounted stem 95. The stem 95 is mounted to move in ears 96 and 97 projecting from the frame and resiliency is imparted to the platen by means of a spring 98 surrounding the lower part of the stem 95 and resting upon the lower ear 97. A pin 99 extending through the stem 95 adjacent to its lower end restricts upward movement of the platen by abutting against the underside of the lower ear 97. To hold 50 the platen in proper alignment, it is provided with a guide member in the nature of a downwardly projecting stem 100 which slides in the upper ear 96 as the platen is pressed downwardly by pressure from above, 55 or raised under the impulse of the spring 98.

The platen 94 is longitudinally slotted as at 101 and entering into said slot is a tape 102 which extends about a pin 103 in the stem 95. The tape 102 extends over a roller 104 mounted in the end of each of the band-folding fingers 89 and 90. The tape extends over other rollers 105 one of each of said rollers being mounted on the pivot pins 91 and 92 of the band-folding fingers 89 and 90. The tape then extends downwardly and has 70 each of its ends connected to a spring 115 which holds the tape under tension at all times. The end of each of the springs 115 is attached to a lug 106 which projects laterally from an arm extending from the hubs 83 of the band folding arms 81 and 82. The tape 102, which is continually under tension by means of the springs 115, co-operates with the band-folding fingers to wrap a 75 band 108 about the cigar 23.

80 From the foregoing the operation of my improved cigar banding machine will be readily understood.

85 The cigar bands 108 are placed in a stack 90 42 in the cigar band magazine with their underside uppermost, so that the gummed end 109 of each band is in position, with the band picking finger 57 resting on the gummed end of the uppermost band in the stack 42.

95 In Figure 1 the machine is shown at the beginning of its cycle of operation. The cigar supporting table 63 is there shown in its horizontal position and it supports a 100 cigar 23 in position ready to be banded. The band picker 57 is shown with the moistened end of the wick 58 resting upon the gummed end 109 of a cigar band. As the drive shaft 6 begins its rotation it drives, 105 through the medium of the interrupted gear 15, the gear 17 which acts through the crank arm 18 and link 19, to lower the clamping arm 20, the arm 28 and consequently the band magazine. It will be understood that while this operation is being performed the band folding mechanism is in a stationary 110 position by reason of the fact that the interrupted gear 14 which drives the folding mechanism has at this period, its toothless part adjacent the gear 75 and consequently 115 does not drive this gear. In addition, the gear 75 is provided with a gear lock in the nature of a sliding shoe 116 which rests against and slides on a segment 117 on the gear 14 while the toothless portion of the gear 14 is adjacent the gear 75.

120 As the cigar-clamping arm 20 and band magazine start downward a cigar band adheres to the end of the wick 58 in the picker 57 and the picker is moved backward by means of the cam 49. This backward movement causes the band to be moved to a position directly over the platen and the tape 102.

125 As the downward movement of the arm

20 continues its foot 22 is brought into contact with the cigar 23 and the cigar is pushed downward thereby, the table 63 moving with the cigar about its pivot 62. As the cigar moves downwardly it strikes the band 108 held on the picker 57 and strips it therefrom, carrying it down to rest on the platen 94 and on top of the tape 102. At this time the mechanism has reached the position shown in Figure 2 and the band folding operation begins.

The gear 17 is now brought to rest by reason of the fact that the toothless portion of the interrupted gear 15 is opposite said gear 17 and said gear 17 is further locked against movement at this point by means of its locking shoe 118 which now slides on the segment 119 on the gear 15. The toothed portion of the gear 14 now meshes with the gear 75 and begins to drive it. The operation of the band folding mechanism is disclosed in Figures 8, 9 and 10. It will be seen that the ungummed end 110 of the band is first folded about the cigar by the finger 89, the tape 102 under tension providing a means for uniformly and snugly fitting the band about varying sizes of cigars. After the ungummed end 110 of the band is folded as disclosed in Figure 9, the gummed end 109 is folded thereover. This is performed by the finger 90 and while said finger 90 is folding down the gummed end 109 the finger 89 moves away from the finger 90 and backward over the ungummed end 110 of the band which it has applied. This is disclosed in Figure 10 and completes the banding operation, after which the banded cigar is removed by hand, or any suitable mechanism, and the band magazine is again elevated and the mechanism of the machine returns to position disclosed in Figure 1.

As fast as the bands are removed from the magazine the bottom or supporting member 40 of the magazine is elevated to keep the uppermost band in proper position to contact with and be received by the band picker 57. To stop and upper limit to the height of the band pile 42, I provide a stop or gauge 111 which is in the nature of a plate projecting from the under face of the table 63. This stop 111 restricts the height of the band pile 42 and likewise provides uniform pressure thereon. Inasmuch as the picker 57 strikes against one end of the band pile, the stop 111 is made to contact with the other end, whereby pressure on the band pile is equalized.

The degree of vertical movement of foot 22 is such that if no article rested on table 63, said foot would move the table down to a point where fingers 89 and 90 could just move over said table. If now an article of say, one half inch height is positioned on the table, the latter would be moved down by foot 22 engaging said article to a point

one-half inch lower than in the first case, and fingers 89 and 90 would just be able to move over said article. Similarly, if the article were one-quarter or one-eighth of an inch in height the table would be moved 70 down one-quarter or one-eighth of an inch further than if said article were not positioned thereon, and in each case the fingers 89, 90 would just be able to move over the article regardless of its thickness. The 75 mechanism for positioning the cigars in banding position is thus self-adjusting for cigars of various thicknesses.

Having described my invention, what I claim is:—

1. In a machine of the class described the combination of a band picker, a band magazine movable to and from said picker, a cigar support, band applying means and means for lowering said cigar and its support to cause said cigar to be brought to the band applying means with a band.

2. In a machine of the class described, a cigar support, a band magazine, means for removing a band from said magazine and carrying the same to a position below the cigar on its support, means for lowering the cigar and causing the band to be carried with it, and cigar banding means adapted to receive said cigar and band and apply said band to the cigar.

3. In a machine of the class described, a combination of a cigar band magazine, a movable cigar support, means for causing said cigar support to be lowered simultaneously with the band magazine, a band picker, means for causing said picker to remove a band from the magazine and carry the same to a position below the cigar on its support, and band applying means adapted to receive the band and a cigar and apply the band to the cigar.

4. In a machine of the class described, band applying means, a support for a cigar, means for holding said cigar on its support while the band applying means acts to apply a band, a band picker, a band magazine, means for causing said picker to carry a band to the band applying means for application to a cigar, and means for moving the band magazine to and from the band picker.

5. In a machine of the class described a combination of band applying means, a movable support on which a cigar is placed, 120 means for causing said support to carry the cigar to the band applying means, a movable band magazine and means for receiving a band therefrom and adapted to carry the same to the band applying means.

6. In a machine of the class described, a pivoted support for a cigar, positioning guides thereon, means adapted to contact with a cigar resting on said support and move said cigar and support downward, and band applying means adapted to receive a

portion of said cigar while held on the support and adapted to apply a band thereto.

7. In a machine of the class described, a band applying means, means for carrying a 5 cigar band to a position adjacent to said band applying means, a cigar support and means for causing said support to be lowered and means for causing a cigar held on said support to contact with the band and remove 10 the same with the cigar to the band applying means.

8. In a machine of the class described, a cigar support adapted to hold a cigar, band applying means adjacent to said support, a 15 cigar clamping means adapted to contact with the cigar on its support and cause the same to be moved to band applying means, a band magazine, means adapted to remove a band therefrom and carry said band to 20 the band applying means, and means for simultaneously raising and lowering the band magazine and the cigar clamping means.

9. In a machine of the class described, a 25 band picker, a band magazine containing a stack of bands the uppermost of which is adapted to be brought into contact with said picker, band applying means, means for moving said picker and an attached band 30 to said band applying means and means for moving the band magazine to and from the picker.

10. In a machine of the class described, the combination with a pivoted cigar support, cigar banding means below said support, a band magazine below said support, a band picker for receiving a band from the magazine and moving the same to a position below the cigar whereby said band is applied to the cigar by the band applying means, means for contacting with the cigar and causing it to be carried with its support to the band applying means, and means for simultaneously lowering the band magazine 45 with the downward movement of the cigar moving means.

11. In a machine of the class described, band applying means, comprising a resiliently mounted cigar support, means for 50 carrying a band to a position below a cigar to be placed on said support, whereby said cigar on its downward movement brings said band to rest upon the resilient support and means for wrapping said band about the 55 cigar.

12. In a machine of the class described, a pivoted table, band applying means below said table, a reciprocating band magazine and means for contacting with a cigar and 60 forcing the same downward with its support to the band applying means and causing a simultaneous lowering movement of the band magazine.

13. In a machine of the class described, 65 a band applying means, a band magazine,

means for receiving a band from said magazine and carrying the same to the band applying means, means for raising a stack of bands in the band magazine in position to contact with the band removing means, said 70 band raising means comprising a movable bottom for the magazine, a stem thereon, means for engaging and supporting said stem, a plate surrounding said stem and means for contacting with said plate during 75 movement of the band magazine and causing said plate to grip said stem and shift the same upward relative to said engaging and supporting means.

14. In a machine of the class described, a band picker, band applying means, a band magazine, means for causing the picker to receive a band from said band magazine and carry the same to the band applying means, means for raising and lowering a stack of bands contained in the band magazine comprising a movable bottom in said magazine, a stem depending therefrom, guides in which said stem is frictionally supported, a gripping member for said stem, an abutment adapted to contact with said gripping member and cause it to shift the stem upwardly relative to said guides upon the downward stroke of the bottom.

15. In a machine of the class described, a movable support for a cigar, means adapted to contact with a cigar while held on said support, and move said cigar and support downward, band applying means below the cigar adapted to receive the same, and a 100 support adapted to receive a portion of said cigar together with a cigar band.

16. In a machine of the class described, a movable support for a cigar, means adapted to contact with said cigar while held on its support and move it and its support, means for holding a cigar band in the path of the cigar, and band applying means adapted to receive said band and cigar and apply the 105 band to the cigar.

17. In a machine of the class described, a cigar supporting member, a band holding member adapted to hold a cigar band in the path of movement of a cigar held on the supporting member, band applying means 110 and means for moving the cigar and its support to cause the cigar to contact with and bring the cigar band to the band applying means.

18. In a machine of the class described, band applying mechanism, a cigar support, means for moving said support with a cigar held thereon to the band applying mechanism, a band magazine, a band picker adapted to rest on the uppermost band held in 115 said magazine, means for causing said picker to adhere to the gummed end of said band, means for moving the band magazine away from said band picker leaving the uppermost band held by said picker, and means 120

for causing said picker to carry the band held by it to a position in the path of movement of the cigar on its way to the band-applying means.

5 19. In a device of the character described, a cigar band applying mechanism, an oscillating support adapted to receive a cigar and move with it to effective bending posi-

tion, means for producing movement of said support and gravity actuated means for yieldingly opposing movement of said support.

Signed at the city, county and State of New York, this 30th day of November, 1920.

FRANCIS X. MALOCSTAY.
